CLAIM

The ornamental design for a cigarette merchandiser, as shown and described.

DESCRIPTION

FIG. 1 is a front elevational view of a cigarette merchandiser showing my new design;

FIG. 2 is a rear elevational view thereof;

FIG. 3 is a left side elevational view thereof;

FIG. 4 is a top plan view thereof;

FIG. 5 is a bottom plan view thereof; and,

FIG. 6 is an enlarged fragmentary perspective view of a portion of FIG. 1, showing details of a cigarette package supporting wire structure therein.
